INVENTOR:
ANTHONY E. CARLSON,
BY *Ed. Mann*
ATTORNEY.

UNITED STATES PATENT OFFICE.

ANTHONY E. CARLSON, OF LOS ANGELES, CALIFORNIA.

BUTTOCKS ELEVATOR.

Application filed August 30, 1926. Serial No. 132,335.

My invention relates to hospital equipment and particularly to a buttocks elevator.

The most disagreeable experiences in hospitals are probably those attendant to the using of bedpans. The bedridden patient must be raised by the nurse or assistant and the bedpan placed under him in the proper position. This procedure is very discomforting for the patient, often causing him 10 severe pains, and on the other hand is very strenuous for the nurse or assistant.

It is an object of this invention to provide a device for elevating the buttocks so that a bedpan may be placed beneath the patient 15 and removed without disturbing the patient.

It is another object of the invention to provide a device of the character mentioned which may be readily removed from depressed into elevated position and vice versa.

20 It is also an object of this invention to provide a novel form of bedpan for use in conjunction with the elevator of the invention.

A still further object of the invention is to 25 provide a bedpan having a projectable shield.

Other objects and advantages of the invention will be made evident hereinafter.

Fig. 1 is a view illustrating the use of the 30 invention, the elevator being shown in collapsed or depressed position.

Fig. 2 is a diagrammatic view similar to Fig. 1 showing the device in elevated position.

35 Fig. 3 is a cross section taken through the device in elevated position, showing the novel bedpan of my invention in place.

Fig. 4 is an enlarged section of the elevator taken as indicated by the line 4—4 of Fig. 3.

40 Fig. 5 is a section taken on the line 5—5 of Fig. 4.

Fig. 6 is a plan view of the device in elevated position.

45 Fig. 7 is a section taken on the line 7—7 of Fig. 3 showing the construction of the shield of the bedpan.

50 Referring to the drawings in detail and particularly to Figs. 4, 5 and 6, the buttocks elevator of my invention has a lower member 11 and an upper member 12 which are hinged together by a hinge shaft 13. The lower member 11 has a flat lower plate 15 from the opposite edges of which flanges 16 are extended upward. The upper mem-

ber 12 has a flat upper plate 17 from the opposite edges of which flanges 18 are extended downward. The pivot shaft 13 is extended through openings 20 formed in the flanges 16 and 18 at the extreme rear ends thereof. 60 As shown in Figs. 3 to 6 inclusive the upper member 12 is provided with an opening 21 in the plate 17 thereof at the front part of the buttocks elevator.

Extended across the forward part of the 65 lower member 12 and carried by the flanges 16 thereof, as clearly illustrated in Fig. 4, is a shaft 23. Rotatably carried on the shaft 23 is a pair of bushings 24 which are placed immediately inside the flanges 16. The 70 bushings 24 carry a sleeve 25 which at the central part is flattened to provide an engagement portion 26. Extending from the opposite ends of the sleeve 25 are arms 27 which may be welded to the sleeve 25 or secured thereto in any other suitable manner. The outer ends of the arms 27 are provided with bearing pins 28 which support rollers 30. The rollers 30 are adapted to engage, a 75 lower face 31 of the upper plate 17 of the upper member 12 directly inside the flanges 18. Extending inward below the forward parts of the flanges 18 are guard lips 33 which prevent a displacement of the rollers 30. Curved downward at the forward 80 part of the upper plate 17 adjacent to the rollers 30 are stop flanges 34 which prevent the rollers from passing forwardly out of engagement with the lower face 31 of the upper plate 17. Bent downward from the 85 upper plate 17 in back of the opening 21 is a resilient finger 36 and bent upward from the lower plate 15 is a spring arm 37 which is positioned directly below the resilient finger 36. The parts of the invention are 90 moved from the position shown in Fig. 1 into the position shown in Fig. 2 by swinging a wrench 41 (Fig. 1) in the direction of an arrow 43 into the position indicated by dotted lines 44 in Fig. 2. The rollers 95 30 mounted at the outer ends of the arms 27 move upward and forward along the lower face of the upper plate 17. The upper member 12 is therefore swung on the hinge shaft 13 so that the forward end thereof is raised. 100 When the rollers 30 reach the position shown in Fig. 2 and also in Fig. 5, they come into contact with the stops 34 which prevent a further forward movement. The arms 27, 105 however, are by this time swung beyond a 110

line perpendicular to the plane in which the upper member 12 is resting and therefore there will be no danger of accidental collapsing of the buttocks elevator.

5. When the buttocks elevator is in the position shown in Fig. 2, the patient is lifted so that there is a space beneath him into which a bedpan, as indicated at 46 (Fig. 3) may be placed. It will be seen that even though the 10 patient is lifted a considerable distance, this lifting action is very easily accomplished by swinging the lever 41 which may be removed thereafter without causing any undue discomfort to the patient and without any material exertion on the part of the nurse or attendant. It should be further noted from Fig. 2 that the patient rests in a comparatively comfortable position. This is because of the fact that the bed is depressed below 20 the front end of the lower member so that the upper member has but little tilt relative to a horizontal plane. There are no sharp edges which will press against the patient's back, causing him any pain or any 25 uncomforatableness.

Referring to Fig. 3, the bed pan 46 consists of a pan portion 47 having a flat lower wall 48 and an upper wall 49 which slopes toward the bottom wall 48 as the forward 30 part of the bedpan is approached. This gives a wedge-shape to the bedpan which is complementary to the shape of the opening formed between the lower and upper members 11 and 12.

35. When the bedpan 46 is installed in place the spring arm 37 engages the lower face 48 and the resilient finger 36 engages the upper face 49, thus securely retaining the bedpan in proper position. The upper forward part 40 of the bedpan 46 is provided with a semi-cylindrical portion 51 in which an arcuated and projectable shield 52 is placed. The shield 52 has a spring holding arm 54 which extends rearward from the front end thereof 45 and through an attachment member 55 secured to the outside of the portion 51 of the bedpan 46. This shield 52 may be extended as shown in Fig. 3 and is very useful when douches and enemas have been administered. 50. The bedpan 46 is also provided with an emptying spout 56.

From the foregoing description the value 55 of my invention may be readily appreciated. The elevator of the invention, as has been pointed out, may be readily placed under the buttocks and moved into elevated position with a minimum of discomfort to the patient and a minimum of effort on the part of the attendant. This is quite a contrast when 60 compared to the customary procedure which requires the tugging and lifting of the patient by the nurses or attendants. Another feature of the invention is that the patient does not come in contact with the bedpan, 65 since the bedpan is inserted under the eleva-

tor and in this manner the danger of infection is reduced to a minimum. A further advantage of the invention is that the elevator and the bedpan are so designed that a complete seal is formed between these two devices, preventing splashing and soiling of the bed linen.

I claim as my invention:

1. A buttocks support comprising: a lower member; an upper member; means for hinging said members together; a sleeve; a shaft supported by said lower member on which said sleeve is rotatable; arms extending from said sleeve, said arms being movable, upon a rotation of said sleeve, from a position in a plane substantially parallel to said lower member into a position in a plane near right angles to said lower member; and means carried at the outer ends of said arms for engaging and moving said upper member 75 into raised position, thus raising the buttocks.

2. A buttocks support comprising: a lower member; an upper member; means for hinging said members together; a sleeve; a shaft 90 supported by said lower member on which said sleeve is rotatable; arms extending from said sleeve, said arms being movable, upon a rotation of said sleeve, from a position in a plane substantially parallel to said lower member into a position in a plane near right angles to said lower member; means carried at the outer ends of said arms for engaging and moving said upper member 95 into raised position, thus raising the buttocks; and stops carried by said upper member for preventing said means from moving forwardly from engagement with said upper member.

3. A buttocks support comprising: a lower member; an upper member; means for hinging said members together; a sleeve; a shaft 105 supported by said lower member on which said sleeve is rotatable; arms extending from said sleeve, said arms being movable, upon a rotation of said sleeve, from a position in a plane substantially parallel to said lower member into a position in a plane near right angles to said lower member; and rollers carried at the outer ends of said arms for engaging and moving said upper member 110 into raised position, thus raising the buttocks.

4. A buttocks support comprising: a lower member; an upper member; means for hinging said members together; a sleeve; a shaft 120 supported by said lower member on which said sleeve is rotatable; arms extended from said sleeve, said arms being movable, upon a rotation of said sleeve, from a position in a plane substantially parallel to said lower member into a position in a plane near right angles to said lower member; rollers carried at the outer ends of said arms for engaging and moving said upper member 125 into raised position, thus raising the buttocks; and 130

stops carried by said upper member for preventing said rollers from moving forwardly from engagement with said upper member.

5. A buttocks support comprising: an upper, body-engaging member; a lower, bed-engaging member, said members being hingedly connected and adapted, when folded together, to be inserted between the buttocks of a person and a bed upon which he may be lying; and lever means for rotating said members relative to each other to raise said buttocks above said bed.

6. A buttocks support comprising: an upper, body-engaging member; a lower, bed-engaging member, said members being hingedly connected and adapted, when folded together, to be inserted between the buttocks of a person and a bed upon which he may be lying; and a bell crank for rotating said members relative to each other to raise said buttocks above said bed.

7. A buttocks support comprising: an upper, body-engaging member; a lower, bed-engaging member, said members being hingedly connected and adapted, when folded together, to be inserted between the buttocks of a person and a bed upon which he may be lying; lever means for rotating said members relative to each other to raise said buttocks above said bed; and means for retaining said members in open position.

8. A buttocks support comprising: an upper, body-engaging member; a lower, bed-engaging member, said members being hingedly connected and adapted, when folded together, to be inserted between the buttocks of a person and a bed upon which he may be lying; a bell crank for rotating said members relative to each other to raise said buttocks above said bed; and means for retaining said members in open position.

9. A buttocks support comprising: an upper, body-engaging member; a lower, bed-engaging member, said members being hingedly connected and adapted, when folded together, to be inserted between the buttocks of a person and a bed upon which he may be lying; and lever means for rotating said members relative to each other to raise said buttocks above said bed, said lever means including arms pivotally mounted upon one of said members and a handle adapted to rotate said arms so as to pry said members apart.

55 10. A buttocks support comprising: an upper, body-engaging member; a lower, bed-engaging member, said members being hingedly connected and adapted, when folded together, to be inserted between the buttocks of a person and a bed upon which he may be lying; and lever means for rotating said members relative to each other to raise said buttocks above said bed, said lever means including arms pivotally mounted upon one of said members and a handle

adapted to rotate said arms so as to pry said members apart, said arms being adapted to engage the other of said members to retain said members in open position.

11. A buttocks support comprising: an upper, body-engaging member; a lower, bed-engaging member, said members being hingedly connected and adapted, when folded together, to be inserted between the buttocks of a person and a bed upon which he may be lying; a shaft rotatably mounted upon one of said members; arms provided upon said shaft; and means for rotating said shaft to cause said arms to separate said members to raise the buttocks of said person above said bed.

12. A buttocks support comprising: an upper, body-engaging member; a lower, bed-engaging member, said members being hingedly connected and adapted, when folded together, to be inserted between the buttocks of a person and a bed upon which he may be lying; a shaft rotatably mounted upon one of said members; arms provided upon said shaft; and a lever for rotating said shaft to cause said arms to separate said members to raise the buttocks of said person above said bed.

13. A buttocks support comprising: an upper, body-engaging member; a lower, bed-engaging member, said members being hingedly connected and adapted, when folded together, to be inserted between the buttocks of a person and a bed upon which he may be lying; a shaft rotatably mounted upon one of said members; arms provided upon said shaft; anti-friction means provided upon the ends of said arms, there being surfaces provided upon the other of said members with which said means are adapted to contact; and means for rotating said shaft to cause said arms to separate said members to raise the buttocks of said person above said bed.

14. A buttocks support comprising: an upper, body-engaging member; a lower, bed-engaging member, said members being hingedly connected and adapted, when folded together, to be inserted between the buttocks of a person and a bed upon which he may be lying; a shaft rotatably mounted upon one of said members; arms provided upon said shaft; means for rotating said shaft to cause said arms to separate said members to raise the buttocks of said person above said bed; and means for retaining said arms in a position for separating said members.

15. A buttocks support comprising: an upper, body-engaging member; a lower, bed-engaging member, said members being hingedly connected and adapted, when folded together to be inserted between the buttocks of a person and a bed upon which he may be lying; a shaft rotatably mounted upon one

of said members; arms provided upon said shaft; anti-friction means provided upon the ends of said arms, there being surfaces provided upon the other of said members with 5 which said means are adapted to contact; means for rotating said shaft to cause said arms to separate said members to raise the buttocks of said person above said bed; and means for retaining said arms in a position 10 for separating said members.

16. A buttocks support comprising: an upper, body-engaging member; a lower, bed-engaging member, said members being hingedly connected and adapted, when folded 15 together, to be inserted between the buttocks of a person and a bed upon which he may be lying; a shaft rotatably mounted upon one of said members; arms provided upon said shaft; rollers provided upon the ends of 20 said arms, there being surfaces provided upon the other of said members with which said rollers are adapted to contact; and means for rotating said shaft to cause said arms to separate said members to raise the 25 buttocks of said person above said bed.

17. A bed pan device comprising: a pair of members hinged together and adapted to be inserted between a patient and a bed upon which he lies below the pelvis region of the 30 patient, the hinge axis being disposed substantially beneath the small of the patient's back; and energy multiplying means for separating said members to raise the pelvis region of said patient while he is disposed 35 in a supine position, a bed pan being adapted to be disposed in the space thus formed between said bed and the pelvis region of said patient.

18. A bed pan device comprising: a pair 40 of members of substantially the same length hinged together and adapted to be inserted between a patient and a bed upon which he lies below the pelvis region of the patient, the hinge axis being disposed substantially 45 beneath the small of the patient's back; and energy multiplying means for separating

said members to raise the pelvis region of said patient while he is disposed in a supine position, a bed pan being adapted to be disposed in the space thus formed between 50 said bed and the pelvis region of said patient.

19. A buttocks support comprising: a base member; an elevator member having collapsed and raised positions relative to said 55 base member, said members when collapsed being insertable beneath the pelvis region of a patient when he is reposing in supine position upon a bed; means for raising said elevator member; and a member which may be disposed between the legs of the patient 60 for the operation of said raising means.

20. A buttocks support comprising: a base member; an elevator member having collapsed and raised positions relative to 65 said base member, said members when collapsed being insertable beneath the pelvis region of a patient when he is reposing in supine position upon a bed; means for raising said elevator member; and a lever 70 adapted to be disposed between the legs of said patient and be connected to said raising means so that swinging said lever actuates said raising means.

21. A buttocks support comprising: a base 75 member; an elevator member having collapsed and raised positions relative to said base member, said members when collapsed being insertable beneath the pelvis region of a patient when he is reposing in supine position upon a bed; means for raising said elevator member; and a lever adapted to be disposed between the legs of said patient and be connected to said raising means so that swinging said lever substantially through 80 an arc of a right angle actuates said raising means.

In testimony whereof, I have hereunto set my hand at Los Angeles, California, this 24th day of August, 1926.

ANTHONY E. CARLSON.
